UNITED STATES PATENT OFFICE.

ARMAND A. BONNARD AND JOSEPH F. TAPIE, OF SANTA BARBARA, CALIFORNIA; SAID
TAPIE ASSIGNOR TO SAID BONNARD.

COMBUSTION TURBINE.

Application filed September 6, 1921. Serial No. 498,723.

This invention relates to improvements in a combustion turbine, and refers more particularly to a combustion turbine of the rotary type in which a cylinder is stationary while a 5 rotor bearing upon its outer surface is caused to rotate thereabout due to the impelling force of the exhausted vapors from the cylinders.

Among the salient objects of the invention are to provide a rotary combustion turbine 10 operating somewhat similarly to the action of a turbine motor in that the power or energy is developed from the expansive force of the combustible charge exhausted from a cylinder; to provide an engine which is small and 15 compact and one in which the power is generated by a rotary movement rather than a reciprocatory movement as is the general practice in internal combustion engines.

In the drawings:

20 Fig. 1 is a sectional side view of the engine with parts omitted and parts broken away.

Fig. 2 is an end elevation with parts in section.

Referring in detail to the drawings, the 25 engine cylinder 1 is bored to accommodate the pistons 2, 3 and 4 which have a horizontal reciprocating motion. About the cylinder casting is cored a water jacket 5 through which water as a cooling medium is circulated, introduced through the pipe 6 and 30 drained off through the pipe 7. The outer surface of the jacket has a shoulder portion centrally located on both sides of which are fitted ball bearings 8. These bearings support the rotor 9, to which are bolted the cams 35 10 and 11.

Describing now the operation of the respective pistons, the piston 2, which is fitted in the cylinder and has one or more spark 40 plugs 12 screwed into tapped holes in the piston, is reciprocated by a connecting rod 13 which has a ball socket connection with the piston and an adjustable connection 14 with the rocker arm 15 supported by the block 16 which is mounted on the side of the cylinder 45 casting. The rocker arm 15 receives its rocking motion from a push rod 17, which is bifurcated at both ends to accommodate the rollers 18 and 19, the former contacting the 50 edge of the rocker arm and the latter the cam 10 mounted on the side of the rotor. The rocker arm is kept in operating contact with the roller 18 by means of a spring 20. The piston 3 on the other hand, operating in an 55 opposite direction to the piston 2, is similarly

reciprocated by a connecting rod 21 through a rocker arm 22 and a push rod 23 having rollers operating on the rocker arm and cam 11 in a similar manner to those explained in connection with the operation of piston 2. Seated in the piston 3 are valves 24 and 25 which are caused to seat by the compression springs 26 and 27 and open by contacting with piston 4 on its forward movement. The piston 4 is reciprocated in the cylinder just back of the 60 piston 3 by a rocker arm 28 pivoted at 29 and securing its rocking motion from a push rod 30 which is given a horizontal movement by the cam ring 11 upon which the roller 31 travels. A similar roller 32 at the opposite end 65 of the push rod contacts the rocker arm and the assembly is held in contacting relation or operable position by the spring 33. An inlet port 34 permits the admission of gas to the cylinder between the pistons 3 and 4, when 70 the piston 4 has been reciprocated outwardly from the center of the piston chamber.

Centrally of the cylinder are bored outlet ports 35 which permit the escape of the exhaust gases into the ports 36, which lead 75 through the water jacket, the latter registering with ducts 37 in the rotor which branch into sectional ducts 38 directing the exhaust gases through the rotor into the ducts 39 of the stationary portion surrounding the rotor, 80 the latter discharging the gases through said ducts. Auxiliary exhaust ports 42 are supplied in the cylinder to relieve the cylinder of any excess of dead gases. Pressure rings 85 43 are fitted in grooves on both sides of the 90 power delivering ports 36 in order to prevent the escape of gases about the main bearing.

Describing the operation of the engine, the combustible fuel in the form of vapor is 95 drawn into the space between the pistons 3 and 4 as the piston 4 is moved outwardly toward the end of the cylinder, thereby uncovering the port 34 and permitting the combustible vapor to enter between the two 100 pistons. It will be noted that the connecting rod 21 extends through the body of the piston 4 in a pressure tight fitting produced by contracting brass rings 44 which serve to prevent the escape of the pressure from the compartment between the pistons. 105

The rocker arm 28 is bifurcated to fit about the end of the piston 4 and is provided with slot shown at 45 to provide the necessary play for the piston. 110

4. The movement of the pistons actuated by the push rods contacting the cam rings by means of the rollers, is such that as soon as the combustible charge has been introduced between the pistons 3 and 4, the said pistons are moved inwardly toward the center of the cylinder, the piston 4 covering the intake port 34 and compressing the gas. Simultaneous with this movement, the valve stems of the valves 24 and 25 are contacted by the piston 4 and caused to open, permitting the combustible charge to pass into the main piston chamber 46 of the cylinder. At the same time, the piston 2 has moved inwardly, assisting in the compression of the gases just before the charge is ignited by the spark plugs 12, the piston 4 has moved outwardly to permit the closing of the valves and the introduction of another charge through the inlet 34.

It is understood, of course, that the charge is introduced from any desired type of mixing valve and any number of valves may be placed in the piston 3 in order to permit immediate ingress of the vapors to the combustion chamber. With the explosion of the charge, the exhaust gases pass out through the exhaust ports 35 and into the power delivering ports, thence to the outer moving and stationary vanes of the rotor and casing. It is essential that the gas intake port is a proper distance from the compression center of the cylinder and that the exhaust or power delivering ports are positioned to register properly with the exhaust ports of the cylinder, thereby delivering the power to the rotor at the proper time. The purpose of the piston 4 is to create the same vacuum as would be created in a reciprocating motor of the same size as the combustion turbine on its intake stroke. In addition to this, it compresses the gas taken in and holds it until it moves forward to a position where the valves are open and the charge introduced to the piston chamber. This double compressing of the gas will enable the motor to have a completely mixed charge increasing substantially the economy of fuel consumption. On one side of the rotor is bolted or otherwise fixed a sprocket 47 from which may be run a silent chain (not shown) which serves to transmit the power from the rotor to any desired vehicle or machine (not shown). A second sprocket 48 fixed to the opposite side of the rotor furnishes a means for operating a second silent chain (not shown). The main roller bearings 8 should be sufficiently heavy to support the entire weight of the rotor and provision made for taking up the radial thrust by means of the adjusting rings 49.

The functioning of the machine after each explosion is as follows. The piston 4 on moving outwardly to the end of its vacuum producing stroke draws in a charge of combustible gas in the form of vapor between the pistons 3 and 4. At the end of the outward movement of the piston 4, the piston 3 is practically at the end of its compression stroke. These two pistons moving in opposite directions create the vacuum action that would be created in the full stroke of the common type of motor were there but one piston. Just at the end of the vacuum producing stroke, the piston 4 uncovers the gas inlet port 34 and permits the intake of the combustible charge. The piston 4 then moves in an opposite direction or toward the piston chamber while the piston 3 is drawn toward it. This opposite movement of the two pistons first closes the inlet port and produces the first compression of the combustible gases. When almost at the end of their opposed movements the piston 4 contacts the valve stems and operating against the valve spring tension, permits the compressed gas to pass into the combustion chamber. In the meantime, piston 2 has gone through substantially the same operation as piston 3 except for the valve operation and at the same time substantially that the valves in the piston 3 started opening, the piston 2 opens the auxiliary exhaust ports 42. The onrush of gases coming through piston 3 will force out any remaining exhaust gases from the combustion chamber thereby permitting the ingress of a whole new combustible charge. Pistons 2 and 3 now are caused to move toward each other in an opposed direction due to the cam, rocker arm and push rod arrangement explained and the final compression of the combustible charge takes place. When the high compression point is reached, the charge is ignited by the spark plugs in the piston 2 which are connected with a generator and timing mechanism operable to cause the ignition of the fuel charge at the proper instant. The exhaust of the gases takes place as explained through the ports and the energy expended through the rotary and stationary ducts of the machine. The high parts of the cam rings 10 and 11 will extend for short intervals so as to hold the pistons 2 and 3 stationary for the interval necessary to allow the expanding gas to be exhausted as follows. Simultaneously with the explosion in the combustion chamber, the power delivering ports 35 which permit the gases to enter the ports 36 will be opened by registration with the ducts 37 of the rotor, thus giving an escape for the expanding gas. These gases continue through the vanes through the branch passages 38 where they strike the fins 39 of the stationary shell and rebound to the fins or vanes 40 of the rotor from whence they find complete exhaustion to the atmosphere through the outside fins of the rotor 41. It is understood, of course, that the pistons and the compression piston 4, together with the vanes of the rotor and the positioning of the timing cams with their respective cross heads and push rod arrangement, are such that the mechanism is operated in timed relation so that

the intake and exhaust and the ignition of the charge together with the positioning of the pistons at the different cycles of operation are such that the machine will cause the rotor to function smoothly at all times.

We claim as our invention:

1. In a combustion turbine, the combination with a cylinder having three reciprocating pistons therein, inlet and exhaust ports to said cylinder of a rotor driven by the expanding gases from the cylinder to open and close the exhaust ports in the cylinder at predetermined intervals, means driven from the rotor operating the central piston with one piston for introducing the charge to the cylinder and with the other piston for compressing

- 15

and exhausting the expanding gases after ignition.

2. In a combustion turbine, the combination with a stationary cylinder having three reciprocating pistons therein, inlet and exhaust ports to said cylinder of a rotor driven by the exhaust from the cylinder, operative connections between the rotor and the pistons to cause the centrally positioned piston to co-operate with one adjacent piston in introducing the combustion gases to the cylinder and with the other in compressing and exhausting the gases from the cylinder subsequent to ignition.
